Des. 218,350

Patented Aug. 11, 1970

218,350

NOVELTY DRINKING VESSEL

Robert Paul Marks, 2554 W. Rosemont Ave.,
Chicago, Ill. 60645

Filed July 18, 1969, Ser. No. 18,270

Term of patent 7 years

Int. Cl. D7—01

U.S. Cl. D44—9

FIG. 1 is a side elevational view of a novelty drinking vessel showing my new design.

FIG. 2 is a top plan view thereof.

FIG. 3 is a bottom plan view thereof.

FIG. 4 is an end view thereof.

I claim:

The ornamental design for a novelty drinking vessel, substantially as shown.
